UNITED STATES PATENT OFFICE.

ANTON J. ROLLERT, OF CHICAGO, ILLINOIS, ASSIGNOR TO THEODOR A. KOCHS, OF SAME PLACE.

DESIGN FOR A BARBER'S CHAIR.

SPECIFICATION forming part of Design No. 20,925, dated July 7, 1891.

Application filed June 15, 1891. Serial No. 396,378. Term of patent 3½ years.

To all whom it may concern:

Be it known that I, ANTON J. ROLLERT, a citizen of the United States, residing at Chicago, in the county of Cook and State of Illinois, have invented a certain new and useful Design for Barbers' Chairs; and I do hereby declare the following to be a full, clear, and exact description of the invention, such as will enable others skilled in the art to which it appertains to make and use the same.

The design consists in the novel configuration and ornamentation for a barber's chair, as hereinafter set forth, and shown in the drawing.

15 The drawing is a perspective view of a barber's chair embodying my novel design. Referring to said drawing, A indicates the base of the chair, and B the body portion thereof. The said body portion is provided 20 in a familiar manner with the seat, back, head-rest, and the arms 1. At the forward end of each arm is placed an upright pillar 2, that rises from the side of the seat of the chair. A knob 3 rises from the upper end of 25 the pillar 2 above the arm of the chair. The pillar 2 is located slightly in the rear of the front edge of the seat, and at the front corners of the seat and in front of the pillars 2 are located upright posts 4, which rise to about

one-half the height of the said pillars. The 30 said pillars are plain, while the posts are round and are ornamented by the beads and bulged and narrow portions. From the upper ends of the posts 4 to the upper ends of the pillars 2 extends a curved connecting- 35 piece 5, having scrolls 6 at each end. Between the arms, the sides of the seat, and the pillars are arranged the approximately star-shaped figures 6, resembling somewhat a starfish, the arms of which extend outwardly from 40 a center-piece and meet the arms of the chair, the pillars, and the sides of the seat.

The parts of my design, when constructed and assembled substantially as shown and described herein, serve to add to the appearance 45 of a barber's chair and ornament the same in a highly-effective, symmetrical, and harmonious manner, which is agreeable and pleasing to the eye.

I claim as my invention—

The design for a barber's chair, substantially as shown and described.

In testimony whereof I affix my signature in presence of two witnesses.

ANTON J. ROLLERT.
